UNITED STATES PATENT OFFICE.

HARRY GURWITZ, OF PROVIDENCE, RHODE ISLAND.

CONDUCTOR'S VEST.

Application filed August 26, 1925. Serial No. 52,483.

To all whom it may concern:

Be it known that I, HARRY GURWITZ, a citizen of the United States, residing at Providence, in the county of Providence and 5 State of Rhode Island, have invented certain new and useful Improvements in Conductors' Vests, of which the following is a specification.

My invention relates to vests adapted primarily to the use of conductors.

The essential objects of my invention are durability; resistance to excessive wear particularly at points of greatest use; strength; and adaptability for supporting coin boxes, 15 hand register machines, and the like.

To the enumerated ends essentially my invention consists in such parts and in such combinations of parts as fall within the scope of the appended claims.

20 In the accompanying drawings which form a part of this specification—

Figure 1 is a front elevation of a vest embodying my invention,

Figures 2 and 3, sections of the same on 25 lines 2—2 and 3—3 respectively of Figure 1,

Figure 4, an enlarged section on line 4—4 of Figure 1, showing in side elevation a coin box mounted in the vest, and

30 Figure 5, an enlarged fragmentary section of an intermediate portion of the vest on a portion of line 3—3 of Figure 1, and showing in section a belt plate engaging the vest, and supporting a hand register shown in side elevation.

35 Like reference characters indicate like parts throughout the views.

My vest or shield consists of a body 8 centrally cut away at the top, as at 9, to accommodate the wearer's neck, and forming vertically extended portions 10. The central and lower portions of the body are preferably broader than the upper portion.

The described contour of the vest is not essential.

40 The body 8 comprises a layer 12 of canvas or similar material constituting a lining and engaged to a compound or composite facing layer, represented generally by 13, by horizontal and vertical lines of stitching.

45 The facing layer 13 is composed of pieces of corduroy supplemented at certain points with overlapping, superposed or auxiliary strips or pieces of leather. The corduroy and leather materials are relatively arranged and disposed as hereinafter set forth.

Extending transversely of the upper portion of the body is a corduroy piece 15 whose lower edge is overlapped by a transversely disposed strip of leather 16. The upper edge of the leather strip is attached through the piece 15 to the back or lining 12 by stitching 18. The lower edge of the strip is attached by stitching 19 directly to the lining. The strip 16 forms a guard for the lower margin of the piece 15 and constitutes a part of the back of a series of three pockets indicated generally by 20, 21 and 22 respectively in horizontal alignment with each other. The front walls of the three pockets are formed by a horizontal transversely disposed piece 24 of corduroy extending across the body, having a rectangular vertically offset middle portion 25. Overlapping the lower margin of the piece 24 throughout its extent is a horizontal leather strip 27. A line of stitching 28 binds the upper edge of the strip 27 to the lining 12 through the lower margin of the piece 24. A similarly disposed line of stitching 29 along the lower edge of the strip 27 binds the latter to the lining 12. The leather strip 27 thus covers the lower margin of the strip 24. The line of stitching 28 defines the lower ends of the pockets 20, 21 and 22. The upper edges of each of the above pockets have an inner facing or guard consisting of a horizontal leather strip 30 opposite the strip 16 at the point of maximum wear upon the mouth of the pocket. It is desirable, for the comfort of the operator's hand that the strip 30 do not present a raw upper edge and that a portion of its attaching stitching be concealed. Therefore at the top of each pocket the upper edges of the strips 24 and 30 have their marginal portions 31 and 32 respectively brought together and united by a line of stitching 33. Thereafter the free edge of strip 30 is downwardly turned and attached at its lower edge by a line of stitches 34 to the pocket wall 24. Thus the stitches 33 and the upper raw edges of the pocket material are concealed, and a smooth entrance to each pocket insured.

The strip 27 forms a portion of the backing of three horizontally disposed pockets indicated in a general way by 36, 37, and 38 whose front walls are formed by a transversely disposed piece 39 of corduroy having its lower margin overlapped by a horizontal leather strip 40. A line of stitches 41 binds

the lower edge of the strip 40 to the lining 12 through the lower margin of the piece 39. The line of stitching 42 defines the lower ends of the pockets 36 and 38, while the 5 stitching 41 defines the lowermost portions of the intermediate pocket 37. The upper edge of each pocket 36, 37 and 38 has an inner horizontal facing or guard strip 44 of leather opposite the leather strip 27, and attached to the upper portion of the pocket wall in the manner described in connection with pockets 20, 21 and 22.

It will be noted that the upper part of the central portion of the leather strip 40 is not 15 stitched whereby there is formed the outer wall 46 of an auxiliary pocket 47 exterior of the pocket 37. A guard piece 49 of leather is fixed by marginal stitches 50 to the front of the outer wall of the pocket 37 and 20 extends both above and below the upper edge of the pocket wall 46, forming a protection for the covered fabric and facilitating the introduction of articles into the pocket.

Two vertical leather strips 53 spaced from 25 each other extend downwardly, at each side of the center of the body, from the neck recess 9 to the bottom edge of the strip 40, passing over the front faces of the piece 15, strip 16, piece 24, strip 27, piece 39, and strip 30 40. The strips are held by lines of stitches 55 upon their inner edges, and similar stitches 56 upon their outer edges; both lines engaging the lining 12. The stitches 55 define the sides of the central pockets 21, 37, 35 and 47, while the stitches 56 define the inner sides of the lateral pockets 20, 22, 36 and 38. Attached to the lower portions of the strips 53 are longitudinally disposed facing strips 58 of leather fixed in position by lateral 40 stitchings 60. These strips are open at their tops and thus form vertical sockets 61.

The strip 40 forms a backing for the upper portions of two pockets 64 and 65 extending across the lower portion of the body. 45 The front walls of these pockets are formed by a piece 67 of corduroy. The upper inner edge of each pocket 64 and 65 has attached thereto, in the manner hereinabove described in connection with the pockets 20, 21, and 22, a leather strip 69. The inner sides of the pockets 64 and 65 are defined by the stitching 70 upon opposite sides of a vertical leather facing strip 72, which stitching passes through the lining 12 and all intervening 50 layers of material. The bottoms and outer sides of the pockets 64 and 65, as well as the outer sides of the pockets 20, 22, 36 and 38, are defined by a line of stitching to the lining 74 extending entirely around the margin 55 of the body. This stitching supplements a parallel concealed line of stitching 75 in attaching a peripheral binding 77 to the body.

The described vest may be supported in any usual or convenient manner. In the 60 present instance shoulder straps 80, adapted

to be crossed have their inner ends sewed to the extended portions 10 of the vest, and carry upon their outer ends clips 81 adapted to detachably engage buttons 82 fixed to the vest margin. A waist belt 84 has one end 70 sewed to the lower lateral portion of the vest, and a clip 85 upon its other end is adapted to engage a button 86 upon the opposite portion of the vest.

Pockets 20, 22, 36, 38, 64 and 65 are adapted for containing moneys of various denominations, and pockets 21, and 37, for transfer slips or pads. In Figure 4 is shown in side elevation a coin receptacle 88. The usual pair of hooks or prongs 89 upon the back 89 thereof are adapted to be received and supported in the two sockets 61.

In Figure 5 is shown in transverse section the back plate 91 upon which is fixed the front plate 92 of the usual holder 93 for a hand cash register 94 whose hook 96 is shown seated in its holder. It will be noted that the lower margin of the holder 93 is supportable in the leather pocket 47 and that the leather facing 49 of the pocket protects the vest from the metal holder.

I claim:—

1. In a vest of the type set forth, a lining, pockets comprising back walls formed by the lining and front walls fixed to the lining, 95 horizontal leather strips fixed to the lining above the pockets and extending behind the front walls, horizontal leather strips having their upper margins folded inwardly with inwardly folded margins of the front walls, 100 stitches connecting the folded margins of the walls and strips, and a seam connecting the unfolded edges of the last mentioned strips with the backs of the front walls below the stitches.

2. In a vest of the type set forth, a lining, a horizontal facing piece extending horizontally across the lining, a leather horizontal guard strip overlapping the facing piece and fixed to the lining, a pocket piece 110 parallel to the facing strip and below the same extending across the lining and fixed at its lower margin to the lining to form the bottoms of pockets, a second horizontal leather guard strip overlapping the bottom 115 of the pocket piece attached to the lining, a second pocket piece below the first pocket piece extending across the lining attached at its lower margin to the latter to form the bottoms of pockets, and overlapping the second guard strip, spaced vertically disposed leather strips extending across the facing piece, pocket pieces and guard strips, and seams in the vertical strips extending into the lining through the pocket pieces 120 to form inner side walls for the pockets, and seams connecting the ends of the pocket pieces to the margins of the lining to form outer side walls for the pockets.

3. In a vest of the type set forth, a lining, 125

5 a horizontally disposed pocket piece extending across the lining and attached thereto at its bottom and ends by rows of stitching, vertically disposed leather strips spaced from each other extending across the pocket piece, stitching extending longitudinally of the strips engaging the lining through the pocket piece and defining the inner sides of the pockets, and vertical leather facing 10 strips stitched at their lateral margins to the first mentioned strips to form vertical sockets.

4. In a vest of the type set forth, a lining, a horizontally disposed pocket piece of textile material extending across the lining and attached thereto at its ends by stitching defining the outer sides of the pockets, a horizontal leather strip overlapping the

lower margin of the pocket piece, a line of stitching extending continuously along the 20 lower edge of the strip engaging the lining, and a second row of stitching extending along the upper edge of the strip except at its central portion to form the mouth of an auxiliary pocket, a leather guard piece 25 fast to the pocket piece extending into the mouth of the auxiliary pocket, vertically disposed leather strips spaced from each other extending across the pocket piece and the horizontal strip and stitching in the 30 vertical strips engaging the lining defining the inner sides of the pocket, the pocket piece and the sides of the auxiliary pocket.

In testimony whereof I have affixed my signature.

HARRY GURWITZ.
